G. E. THACKRAY.
REINFORCEMENT FOR CONCRETE.
FILED MAY 24, 1920.

UNITED STATES PATENT OFFICE.

GEORGE E. THACKRAY, OF WESTMONT BOROUGH, PENNSYLVANIA.

REINFORCEMENT FOR CONCRETE.

Application filed May 24, 1920. Serial No. 383,623.

To all whom it may concern:

Be it known that I, GEORGE E. THACKRAY, a citizen of the United States, and a resident of Westmont Borough, county of Cambria, and State of Pennsylvania, have invented certain new and useful Improvements in Reenforcements for Concrete; and I do hereby declare the following to be a full, clear, and exact description of the invention, such as will enable others skilled in the art to which it appertains to make and use the same.

My invention relates to a type of metal reinforcement for concrete, with special reference to the coiled style of rod used for reinforcing columns or struts for use in buildings, piles, or other similar constructions.

This reenforcement consists of a continuous spiral helix formed from a metal rod or bar of any form or shape desired, which is made into a helix or spiral by bending upon a mandrel or otherwise and the rods forming the coil may be of any size, and the distance between the coils or pitch may be of any distance to suit the design. In order to maintain the coil in position preparatory to placing concrete around it and to enable shipment of the same without deformation it is provided with two or more stiffener members, which are secured to all or part of the individual coils and serve to strengthen the same and to maintain any pitch or distance apart of the individual coils as desired. The reenforcement when in use is in the form of a skeleton of circular shape, the coils being secured to the stiffening members with a slight clearance or looseness so that the coils can be collapsed or flattened or made compact for shipment, and opened or restored to cylindrical form preparatory to being placed in position in the structure.

I ordinarily use two stiffener members arranged at opposite sides of the coil, but three or more can also be used, as will be readily understood.

When more than two stiffener members are used, and it is desired to collapse the structure, the stiffeners are slid together or diametrically opposite prior to collapsing the structure, and the coil can afterwards be opened to its cylindrical form preparatory to setting the same in place and putting in concrete. These stiffening members hold the coil in position while the concrete is being placed also and serve as longitudinal stiffeners in addition to the other longitudinal re-

enforcement. The coil portions are used to resist the bursting pressure and the stiffener members assist in resisting the direct compression, in addition to holding the coils in place.

The forms of stiffener members I use and the manner of connecting them to the individual coils will be more fully described hereafter.

Each stiffener member is preferably composed of two parts, which may either be flats, or angles, an angle and one flat, or two angles, or one channel and one flat, or two channels, or a T bar combined with a U bar, or a flat, or a Z bar combined with a flat, or two angles arranged to form a Z bar, or any combination of sections or bars as may be desired.

Referring now to the details of construction; each of the two bars or shapes forming each stiffening member is provided with a plurality of slots or notches corresponding to the size and shape of the coil rod, the bottom of each slot being preferably of semi-circular form to receive a round coil rod, or of other shape to conform to the section of the rod of other shape, although the slots may be rectangular, the only requirement being that they are slightly larger than the rod which they hold.

The slots may be angular, or curved, or sinuous, or inclined, or straight, but I prefer to make them straight, as this is simpler and in this case the slots in all the bars may be punched or cut by the same tool.

I also prefer to form the slots slightly larger than the coil rod which they surround in order to permit the stiffener bars and coil to collapse for shipment and enable the restoration thereof to a cylindrical form preparatory to use in a structure.

Having thus given a general description of my invention, I will now, in order to make the matter more clear, refer to the annexed sheet of drawings, which forms part of this specification, and in which like characters refer to like parts.

Figure 1 is a side elevation of a portion of one form on my reinforcing member for concrete columns; Figure 2 is a top plan view of the reinforcing member shown in Figure 1; Figure 3 is a side elevation of a portion of one form of stiffener which I may use, drawn on a larger scale; Figure 4 is a transverse section of the form of stiffener shown in Figure 3; Figure 5 is a side elevation of a

portion of another form of stiffener or channel section; Figure 6 is a transverse section of the channel form of stiffener shown in Figure 5; Figure 7 illustrates another form 5 of stiffener member comprising two flat bars secured together; Figure 8 is a transverse section of the stiffener member shown in Figure 7; Figure 9 is a transverse section of another form of stiffener member composed 10 of a channel and a flat bar; Figure 10 is a stiffener member made of a T-bar and a U-bar or a flat bent into U-shape; Figure 11 is a transverse section of Figure 10; Figure 12 is a side elevation of a portion of a Z-bar 15 stiffener with a flat lock bar secured thereto; Figure 13 is a transverse section of the Z-bar and flat lock bar shown in Figure 12; Figure 14 is a side elevation of a portion of a stiffener bar made of a pair of angles; 20 Fig. 15 is a transverse section of the stiffening bar of Figure 14 made of a pair of angles; Figure 16 is a side elevation of a portion of a reinforcing bar of T-shape with a flat lock bar attached thereto; Figure 17 25 is a transverse section of the stiffening bar illustrated in Fig. 16; Fig. 18 is a transverse section of a pair of angles secured together and disposed so as to form a stiffener of Z-shape; Figure 19 is a side elevation of a 30 portion of the bar shown in Figure 18, and Figure 20 is a transverse section of a pair of angles secured together to form a stiffener of channel form. Figures 21 and 22 show a pair of unequal leg angles adapted to form 35 a stiffening member arranged with their longer legs in contact and with their other legs projecting outwardly in opposite directions to form the general shape of a Z-bar. In Figure 21 the outer sides of the longer 40 legs are in contact and in Figure 22 the inner sides are in contact, and these angles may have slots in their longer legs of any of the shapes shown in the other figures.

Referring now to the character of reference on the drawings:—1 is my column reinforcement as a whole. 2 are angular stiffener bars as illustrated in Figures 1, 2, 3 and 4, each angle having a longer leg 3 and a shorter leg 4, 5 is a straight slot or notch in 45 the longer leg in one of the angles, 6 is a curved or bayonet slot in the longer leg of the companion angle, 7 are rivets passing through perforations provided in each angle to secure the two angles together, although 50 instead of rivets, bolts may be used, or I may secure the two stiffener bars together with twisted wires or otherwise; 8 is a helical rod preferably composed of a continuous helix, although I may use separate rings, the ends 55 of which are welded or otherwise secured together; 9 is a stiffener bar composed of two channels as illustrated in Figures 5 and 6, each of the channels having a web 10 and legs or flanges 11.

65 As illustrated in Figures 7 and 8, the stiff-

ener bar is composed of two flats 12, and as illustrated in Figure 9 the stiffener bar is composed of a channel 13 and a flat plate 15; and as illustrated in Figures 10 and 11, the stiffener bar is composed of a T-bar 16 provided with notches 17 in the stem thereof, the other portion of this stiffener bar being composed of a U-shape member 18, which is provided with the notches 19 in the free marginal portions thereof. As illustrated 70 in Figures 12 and 13, the stiffener bar is composed of a Z-bar having web 20 and flanges 21 with a flat bar 22 secured thereto, the Z-bar being provided with the notches 23 and the flat bar with the notches 24. As 75 illustrated in Figures 14 and 15, the stiffener bar is composed of two angles 25, one of which has a straight slot or notch 26 and the other an angular or curved bayonet slot 27. As illustrated in Figures 16 and 17, the 80 stiffener bar is composed of a T-bar 28 provided with notches 29 in the stem thereof in connection with flat bar 30 secured to and having notches 31. As illustrated in Figures 18 and 19, the stiffener bar is composed 85 of a pair of angles placed in position shown, forming a combined section of Z shape, each of these angles 32 being provided with straight notches 33. As illustrated in Figure 20, the stiffener bar is composed of two 90 unequal leg angles 34, each provided with straight notches 35 in the longer legs and secured together with their shorter legs opposite each other, forming a combined section of approximately channel shape. 95

In any of these constructions the two bars forming a stiffener bar may be secured together with rivets or bolts passing through registering holes, or by wires twisted around both members or otherwise as may be desired. 100

One of the particular features of my invention consists in forming stiffener bars of two pieces, each of which is provided with a plurality of slots adapted to partially embrace or surround the coils, or a series of rings or a helix and hold same in any position desired, the two members forming the stiffening bar being secured together in such a way that the individual coils or rings are held in the position desired. The fastening of the stiffening bar to the coils is not firm or rigid, but is provided with a small clearance to allow the bars to move relatively to the coils and the other stiffeners to permit 110 the structure to collapse or to be restored to position as may be desired. 115

My stiffener member may be composed of two bars, each of substantially the same length, one of which may be provided with a 120 plurality of straight slots extending from the one edge thereof and the other may be provided with a similar plurality of curved or angular bayonet slots. When these two bars are superimposed with the slots facing 125 130

in either direction and with the bases of the slots in registry, this forms a plurality of openings, in which the individual coils may be locked or held in position in the bases of 5 the bayonet slots and are so held by contact with the sides of the straight slots, and when the two bars are secured together the coils cannot be displaced. I may also arrange the bars in a somewhat simpler form, namely:—
 10 each bar may have a plurality of straight slots extending from one margin thereof, while the other has a similar plurality of straight slots facing in the opposite direction, and when the two bars are placed together with bases of the slots in registry the coils are held therein. The open slots permit the introduction of the coil rod in an easy and simple manner, and when the slots are closed the coils are held in position desired. I may also make one of these bars in fractional lengths instead of the entire length if so desired.

The slots may also be slightly larger than the coil rod which they hold to allow easy 25 rotation of the parts for collapsing for shipment and restoration of the coil to cylindrical form for use.

Although I have described and illustrated my invention in considerable detail, I do not 30 wish to be limited to the exact and specific details thereof as shown and described, but may use such modifications in, substitutions for, or equivalents thereof, as are embraced within the scope of my invention, or as 35 pointed out in the claims.

Having thus described my invention, what I claim and desire to secure by Letters Patent is:—

1. A reinforcing member for concrete, 40 comprising a helical metal coil, spacing and supporting members each consisting of two portions, each provided with open slots in which the individual coils are inserted, said portions being relatively positioned to close 45 the marginal openings of the combined slots, and means for joining said portions.

2. A reinforcing member for concrete construction comprising a plurality of metal coils substantially parallel and spaced apart 50 at predetermined distances, a spacer and support applied to said coils comprising two bars, each of which is provided with marginal slots, relatively positioned over said coils so as to close the marginal openings 55 of the slots and means for joining each pair of said bars.

3. A reinforcing member for concrete, 60 comprising a helical metal coil, stiffening members secured thereto, each stiffener member being composed of two bars provided with marginal slots facing oppositely and adapted to register with each other, the individual coils being seated in said slots, and means for securing the two component parts 65 of said stiffener bar together.

4. A stiffener for concrete reinforcing members, comprising a pair of superimposed bars with registering marginal slots arranged in opposite directions, thereby forming closed openings, and means for securing 70 the bars together.

5. A stiffener for a concrete reinforcing member comprising a pair of metal bars, each provided with a plurality of open slots the inner ends of which are adapted to register with each other and to receive individual coils seated therein, and means for joining said bars together, whereby the marginal openings of the slots are closed.

6. A stiffener for reinforcing members 80 composed of two metal bars, one provided with a plurality of straight marginal slots, extending inwardly from the edge thereof, the other bar being provided with a similar plurality of bayonet slots extending inwardly from one edge thereof, the bars being superimposed on each other with the bases of the slots in registry, thereby forming a plurality of closed openings in the joined bars, and means for securing the bars together.

7. A stiffener for a reinforcing member comprising a pair of separate bars of flanged form, each provided with a plurality of open slots extending from one margin 95 thereof, said bars being superimposed and relatively positioned to form registering openings at the bases of said slots with their entrances closed, and means for joining the bars.

8. A reinforcing member for concrete, comprising a helical metal coil, spacing and supporting members each composed of two portions provided with marginal slots adapted to receive and support individual coils, said portions being superimposed and relatively positioned so as to close the marginal openings of the slots, and means for joining the portions of said spacing members together whereby the coils are secured and 100 locked in position.

9. A reinforcing member comprising a helical metal coil, spacing and supporting members each composed of a pair of bars each provided with a plurality of slots in 115 which the individual coils are inserted and means for joining each pair of bars together after the coils are in position therein, whereby the entrances to the slots are closed and the coils are supported and spaced apart.

10. A reinforcing member comprising a helical metal coil, spacing and supporting members each composed of a pair of bars each provided with a plurality of open slots spaced apart and adapted to receive the coils and means for joining said spacing members after they are superimposed and relatively positioned to close the slot entrances after the coils are in said slots, whereby the coils are secured in place.

11. A reinforcing member for concrete comprising a helical metal coil, a plurality of supporting and spacing members each composed of a pair of separate bars each provided with a plurality of open slots spaced apart in which the coils are seated, the bars of each pair being superimposed and relatively positioned to close the mar-

ginal openings of said slots whereby the coils are secured and locked in place, and 10 means for securing together the component parts of each spacing member.

In witness whereof I hereunto affix my signature.

GEORGE E. THACKRAY.
